TELEPHONE SYSTEM

Edward H. Lanham, Notre Dame de Grace, Quebec, and Lee R. Waller, Montreal, Quebec, Canada, assignors to Western Electric Company, Incorporated, New York, N. Y., a corporation of New York

Application June 10, 1939, Serial No. 278,404

14 Claims. (Cl. 179—18)

This invention relates to telephone systems and particularly to intercommunicating or conference systems involving the use of loud-speakering and receiving equipment.

It is the object of this invention to provide an improved system of telephone intercommunication involving a plurality of stations which normally have access to and are accessible from a central office, such as a private automatic exchange.

In accordance with a feature of the invention, a system is provided in which the regular private automatic exchange facilities are employed for the additional service of loud-speaker intercommunication.

In accordance with another feature of the invention, an executive at a "primary" station may establish connection and hold conversation with any or all of a plurality of "secondary" or subordinate stations simultaneously by dialing the code numbers of the desired "secondary" stations and may, at any time during an established conversation with one or more "secondary" stations, call in any other "secondary" stations without interference with the connections already established and without necessitating any operation by the subscribers whose stations are already connected to the conference line.

A further feature of the invention resides in the use of means for discriminating between the use of an executive service set and a regular telephone set at the "primary" station whereby a call originated at the "primary" station is automatically extended either to another station of the intercommunicating or conference system or to a central office, depending upon which equipment is employed.

These and other features of the invention will be best understood from a following detailed description made with reference to the accompanying drawings in which:

Fig. 1 illustrates a "primary" station A and a plurality of "secondary" stations B and C each equipped with loud-speaking apparatus used in connections established over the conference or intercommunicating line L, and with facilities for establishing connections to a private automatic exchange by way of the automatic switches illustrated schematically at the right of the figure; and

Fig. 2 illustrates an automatic switch W which is controlled from the "primary" station A in effecting the selective connection of any or all of the "secondary" stations to the line L and also discloses the relay equipment which func-

tions to step the switch W and to transmit call and busy signals. In reading the drawings, Fig. 2 is placed immediately below Fig. 1.

Before entering into a detailed description of the operation of the system disclosed in the drawings, a brief reference will be made to the equipment located at each station; to the normal conditions of the several lines with respect to the intercommunicating or conference line and private automatic exchange apparatus; and to the other equipment employed in completing conference connections and for signaling purposes.

The "primary" station A is equipped with a distant talking transmitter 61, a loud-speaker 41, an amplifier 62, an executive service key 10 and an auxiliary dial 12. This equipment supplements the regular station equipment, diagrammatically indicated at 63, and the dial 19. The "primary" line is normally associated with the conference line L and may be transferred therefrom to the private automatic exchange equipment by the operation of relay 15. The equipment at the "secondary" stations B and C is similar to that at the "primary" station except at no auxiliary dial, such as dial 12, is required. Each "secondary" line, or section individual thereto, terminates in contacts of the line finders S_b and S_c whose contacts are multiplied with the contacts of connector switches C_b and C_c, which switches serve in completing calls incoming to the various stations from the private automatic exchange. The transfer of the "secondary" lines from their private automatic exchange switch terminals to the intercommunicating line L is effected by the combined operations of two relays, such as relays 46 and 50. The stepping switch W which is controlled from the "primary" station may be of any well known type and functions to selectively signal the various "secondary" stations and prepare them for connection to the line L. The actual connection of the "secondary" stations to the line L is accomplished when the subscribers thereto respond to an incoming call signal. The amplifiers which constitute part of the substation equipments may be of any well-known type and are balanced to permit two-way loud-speaker conversation to be carried on freely without the necessity of operating a "press-to-talk" key. Call and busy signals are transmitted to the stations under the control of vibrating reed type relays, such as 35 and 42, which function for a predetermined interval of time to apply a signal of corresponding duration to the called stations.

The operation of the system disclosed in the drawings will now be described in detail.

When the subscriber at "primary" station A desires to converse with the subscriber at a "secondary" station, such as station B, the "executive service" key 10 at the "primary" station is actuated. Actuation of key 10 connects the high impedance retard coil 11 across the "primary" line in series with the pulsing springs of auxiliary dial 12. Relay 13, which is normally connected across the line L, thereupon operates in a circuit extending from grounded battery, upper winding of relay 13, conductor 14 of line L, back contact and inner lower armature of relay 15, winding of marginal relay 16, lower armatures and back contacts of relays 17 and 18, retard coil 11, closed contacts of switch 10, pulsing contacts of dial 12, back contacts and upper armatures of relays 18 and 17, pulsing contacts of the "primary" subscriber's regular dial 19, upper armature and back contact of relay 15, conductor 20 of line L, to ground by way of the lower winding of relay 13. Relay 16, being marginal, does not operate in series with the high resistance retard coil 11. Relay 13, however, does operate and in attracting its upper armature causes relay 21 (Fig. 2) to operate in a circuit extending from grounded battery, winding of relay 21, conductor 22, left armature and back contact of relay 16, conductor 23, to ground by way of the front contact and upper armature of relay 13. At its lower armature relay 13 disconnects ground from conductor 30.

At its inner right armature, relay 21 connects ground to conductor 24 which extends to the sleeve terminals of the switches C and S, thus marking the "primary" station A busy to calls thereto originating at or extended from the central office or private automatic exchange at which the switches are located. At its inner right armature and back contact relay 21 opens the circuit to the lower winding of relay 15. In attracting its outer right armature, relay 21 connects conductor 25 to conductor 26, thereby short-circuiting the winding of marginal relay 16 so that relay 13 is now held operated in a circuit which does not include the winding of relay 16 but includes the outer right armature and front contact of relay 21. The functions performed by the left armatures of relay 21 will appear presently.

After actuating key 10 as just described, the subscriber at "primary" station A manipulates the dial 12 in accordance with the code assigned to the "secondary" station B. Assuming this code to be "3," the subscriber dials the digit "3" in the well-known manner. Relay 13, whose operating circuit includes the pulsing contacts of dial 12, follows the dial pulses. As soon as the dial 12 is moved off normal, the off-normal spring contacts 27A shunt the retard coil 11, removing its impedance from the pulsing loop. Relay 16 does not follow the dial pulses even though the retard coil is effectively shunted because the winding of relay 16 is short-circuited by the outer right armature and front contact of relay 21, as hereinbefore described.

On the first release of relay 13 in response to the actuation of dial 12, relay 28 (Fig. 2) operates in a circuit extending from grounded battery, winding of relay 28, conductor 29, inner left armature and front contact of relay 21, conductor 30, lower armature and back contact of relay 13 to ground. Relay 28 is a slow-to-re-

lease device and remains operated during the pulsing period.

Stepping magnet 31 operates in parallel with relay 28 and follows the repeated releases and operations of relay 13 caused by the manipulation of dial 12. Magnet 31 accordingly functions in a well-known manner, to step the brushes of switch W until they engage the third contact of each level. These contacts are designated on the drawings by the letters b and b', respectively.

When relay 28 operated on the first release of relay 13, it caused relays 32 and 33 to operate in obvious circuits which include the inner right armature and front contact of relay 28. Relay 33, in operating, locks in a circuit extending from grounded battery, its own winding and inner left armature and associated make-before-break contact, conductor 34 to ground at the front contact and outer right armature of slow-to-release relay 32. The functions performed by the other armatures of relays 32 and 33 will appear as the description progresses.

When the dial 12 returns to normal after the dialing of digit "3," relay 28 releases due to the fact that the circuit to its winding remains open at the lower armature and back contact of relay 13. Relay 28 in restoring its armatures opens the circuit to the winding of relay 32. This relay, being slow to release, does not immediately restore its armatures. Before it does so a circuit for relay 35 is completed which extends from grounded battery, winding of relay 35, front contact and left armature of relay 32, conductor 36, left armature and back contact of relay 28, brush and contact b' of switch W, conductors 37 and 38 to the sleeve terminals of the automatic switches C_b and S_b at the private automatic exchange. If the line of "secondary" station B is busy due to an in or out call being established over the regular private automatic exchange equipment, ground potential, in accordance with well-known practice, will be found on the sleeve lead. Relay 35 would thereupon operate in the circuit just traced, before relay 32 releases its armatures.

Relay 35, which is of the vibrating reed type, closes an obvious circuit for slow-to-release relay 39. Due to its vibrating characteristic, the armature of relay 35 maintains relay 39 operated for several seconds after the release of relay 32. In attracting its left armature, relay 39 establishes an obvious circuit for relay 40. Relay 40 operates and at its right armatures and front contacts connects a busy tone signal source to the line L. This signal is reproduced in the loud-speaker 41 at station A to advise the calling subscriber thereto that the called station B is busy. The busy tone current transmitted over line L does not operate relay 18 at the "primary" station A.

If the called station B is not bussed by the private automatic exchange equipment, there will be no ground potential on the sleeve lead 38 and consequently relay 35 will not operate when relay 28 releases upon the completion of dialing.

Assuming the called station B to be idle, relay 28 releases upon completion of dialing, in turn releasing relay 32. Relay 32 opens the locking circuit to relay 33, which relay, however, being slow to release does not restore its armatures immediately so that a circuit is now established which extends from grounded battery, winding of slow-to-release relay 42, left armature and back contact of relay 40, front contact and right

armature of relay 33, to ground by way of the back contact and outer right armature of relay 32. Relay 42 operates in this circuit before relay 33 releases and in turn causes relay 43 to operate in an obvious circuit. Relay 42, like relay 35, is of the vibrating reed type and due to the vibrating characteristic of its armature maintains relay 43 operated for several seconds after the release of relay 33.

At its left armature and front contact relay 43 extends ground potential over conductor 44, brush and third terminal *b* of switch W, conductor 45, winding of relays 46 and 47 in parallel to grounded battery. Relay 47 operates and connects tone current to the called station B which operates the loud-speaker 48 to produce a call signal. Relay 70 does not operate on this tone current. When relay 42 ceases to vibrate and slow-to-release relay 43 has subsequently released its armatures, relay 47 releases and disconnects the tone source from the called station B and the line conductors from station B are extended to the outer armatures of relay 46.

Relay 46, which operated in parallel with relay 47, locks to ground at the outer left armature and front contact of relay 21 by way of conductor 49 and the inner upper armature and make-before-break contacts of relay 46. At its inner lower armature relay 46 connects ground to the sleeve terminals of switches S_b and C_b to make the called line test busy to the regular private automatic exchange equipment. At its outer, upper and lower armatures, relay 46 transfers the tip and ring conductors of the called line from the private automatic exchange equipment and prepares an operating circuit for relay 50.

In response to the tone signal, the subscriber at station B operates station key 51, thereby completing the circuit for relay 50. This circuit extends from grounded battery, upper winding of relay 50, front contact and outer upper armature of relay 46, back contact and upper armature of relay 47, closed contacts of dial 71, upper armatures and back contacts of relays 72 and 70, closed contacts of key 51, coil 52, lower armatures and back contacts of relays 70 and 72, lower armature and back contact of relay 47, outer lower armature and front contact of relay 46, lower winding of relay 50 to ground. The impedance of coil 52 is such as not to interfere with the transmission of speech.

Relay 50 in operating disconnects the station equivalent network 53 from the intercommunicating line L and connects the called station line thereto. The "primary" station A and the "secondary" station B are thus connected together and two-way conversation over the line L may proceed on a loud-speaker basis.

When relay 42 ceases to vibrate and releases relay 43, the rotary switch release circuit is closed from ground at the outer right armature and back contact of relay 28, right armature and back contact of relay 43, right armature and back contact of relay 39, outer left armature and back contact of relay 33, inner right armature and back contact of relay 32, off-normal springs 54 of switch W, winding of release magnet 55 to battery and ground. Release magnet 55 functions in a well-known manner to return the switch to normal.

At the termination of conversation between the subscribers at stations A and B, the subscriber at the "primary" station restores the executive service key 10 to normal whereupon relays 13 and 21 release, allowing relay 46 to restore its

armatures and the circuit is restored to normal.

It will be noted that immediately after the called station B was signaled, the switch W was restored to normal so that it is in readiness to receive further pulses from dial 12 at station A should the subscriber thereat desire to include other of the "secondary" stations in a conference circuit. If during the conversation between the subscribers at stations A and B the subscriber at station A wishes to call in one or more additional "secondary" stations for conference purposes, it is only necessary that the dial 12 be actuated to dial the call number or numbers of the station or stations desired. Such operations do not, in any way, interfere with the connection already established.

Relay 13 will respond to the dial pulses in the same manner as when the "secondary" station was dialed and the consequent relay operation will be the same as already described. The switch W will, of course, be positioned on different bank contacts in accordance with the codes dialed and will operate relays 46 and 47 corresponding to the stations called. In each case, switch W returns to normal after performing its functions either of reporting the called line busy or operating the associated relays 46 and 47 to prepare the called line for connection to the common talking circuit L and to apply a tone signal to the called line.

When the subscriber at "primary" station A desires an outside connection, the receiver of the regular telephone set is removed from its switchhook. Relay 17 thereupon operates in a circuit extending from grounded battery, upper winding of relay 13, conductor 14, back contact and inner lower armature of relay 15, winding of marginal relay 16, over the closed subset loop, winding of relay 17, upper armature and back contact of relay 15, conductor 20 to ground by way of the lower winding of relay 13. Relay 17 operates in this circuit and disconnects the executive loud-speaking equipment from the line. Relay 16 also operates under this condition due to the absence of the high resistance retard coil 11 from the circuit and in turn operates relay 15 over an obvious circuit.

Relay 15 operated transfers the "primary" station A from the line L to the regular private automatic exchange line. At its two lower armatures and front contacts relay 15 shunts down relay 16. Relay 15, however, is held operated in a circuit extending from grounded battery, lower winding of relay 15, conductor 56, back contact and inner right armature of relay 21, conductor 24 to ground on the sleeve terminal of switch S at the exchange. It will be understood that when relay 15 operated, line finder S functioned in the well-known manner to seize the calling line and apply ground potential to the sleeve terminal thereof.

On an incoming call to the "primary" station from the private automatic exchange, relay 15 operates from ground on the sleeve circuit of the private automatic exchange equipment and cuts the private automatic exchange line through to the "primary" station and shunts relay 16. Ringing current transmitted from the private automatic exchange operates relay 18 which functions to cut off the amplifier equipment at the "primary" station during ringing periods. Relay 17 operates when the called subscriber answers the call by removing the receiver from its switchhook and maintains the executive service equipment disconnected from the line.

The subscribers at the "secondary" stations B and C may initiate calls to and receive calls from the private automatic exchange in the well-known manner, by employing the regular telephone set. Relay 12 operates when the receiver at the "secondary" station is removed from its switchhook and cuts off the loud-speaking equipment from the line. Manipulation of the dial 11 causes the switches at the private automatic exchange to function in the well-known manner to extend the connection to a called station.

What is claimed is:

1. In a combined automatic telephone exchange and loud-speaking intercommunicating system, a primary station having a loud-speaking telephone set including a call initiating key and a regular telephone set, an intercommunicating line, a link circuit extending to automatic switches at a central office, and means for discriminating between the use of said call initiating key and said regular telephone set at said primary station in originating a call, whereby a call originated at said primary station is automatically extended over said intercommunicating line or over said link circuit depending upon whether said call initiating key or said regular telephone set is employed in originating a call at said primary station.

2. In a combined private automatic telephone exchange and loud-speaking intercommunicating system, a primary station, a loud-speaking telephone set and a regular telephone set at said station, an intercommunicating line circuit, a central office link circuit, said primary station being normally associated with said intercommunicating line circuit and disconnected from said central office link circuit, switching means responsive to the use of said regular telephone set in originating a call for transferring said primary station from said intercommunicating line and connecting it to said central office link circuit, and means included in said loud-speaking telephone set for rendering said switching means inoperative when said loud-speaking telephone set is employed in originating a call at said station.

3. In a combined private automatic telephone exchange and loud-speaking intercommunicating system, a primary station, a loud-speaking telephone set and a regular telephone set at said station, an intercommunicating line circuit, a central office link circuit, said station being normally associated with said intercommunicating line circuit and disconnected from said central office link circuit, a marginal relay included in circuit between said primary station and said intercommunicating line circuit, switching means controlled thereby, means effective upon the use of said regular telephone set in originating a call for causing the operation of said marginal relay whereupon said switching means operates to disconnect said station from said intercommunicating line and connect it to said central office link circuit, and means including a key associated with said loud-speaking telephone set for rendering said marginal relay unresponsive to the use of said loud-speaking telephone set in originating a call at said station.

4. In a combined automatic telephone exchange and loud-speaking intercommunicating system, an intercommunicating line circuit, a station thereon having a loud-speaking telephone set including a key and a dial, a central office,

an automatic switch thereat having a terminal corresponding to said station, means responsive to the operation of the key at said station for applying a busy potential to said terminal, a second station, means including the dial at said first station for automatically signaling said second station, and means operating when the subscriber at said second station responds to the signal for connecting said second station to said intercommunicating line.

5. In a combined automatic telephone exchange and loud-speaking intercommunicating system, an intercommunicating line circuit, a station thereon having a loud-speaking telephone set including a key and a dial, a second station normally disconnected from said intercommunicating line circuit, a central office, automatic switches thereat having terminals corresponding to said stations, means responsive to the operation of the key at said first station for applying a busy potential to the central office switch terminal corresponding to said first station, means including the dial at said first station for automatically signaling said second station and applying a busy potential to the central office switch terminal corresponding to said second station, and means operating when the subscriber at said second station responds to the signal for connecting said second station to said intercommunicating line.

6. In a combined automatic telephone exchange and loud-speaking intercommunicating system, an intercommunicating line circuit, a station thereon having a loud-speaking telephone set including a key and a dial, a second station normally disconnected from said intercommunicating line circuit, a central office, automatic switches thereat having terminals corresponding to said stations, means responsive to the operation of the key at said first station for applying a busy potential to the central office switch terminal corresponding to said first station, means responsive to the actuation of the dial at said first station subsequent to the actuation of said key for testing the central office switch terminal corresponding to said second station, and means responsive to busy potential encountered on the central office switch terminal corresponding to said second station for applying a tone signal to said intercommunicating line circuit for reception by the loud-speaker at said first station.

7. In a combined automatic telephone exchange and loud-speaking intercommunicating system, an intercommunicating line circuit, a station thereon having a loud-speaking telephone set including a key and a dial, a second station normally disconnected from said intercommunicating line circuit, a central office, automatic switches thereat having terminals corresponding to said stations, means responsive to the operation of the key at said first station for applying a busy potential to the central office switch terminal corresponding to said first station, means responsive to the actuation of the dial at said first station subsequent to the actuation of said key for testing the central office switch terminal corresponding to said second station, and means operating a predetermined interval of time after the central office switch terminal corresponding to said second station is tested and found idle for transmitting a tone signal to said second station.

8. In a combined automatic telephone exchange and loud-speaking intercommunicating system, an intercommunicating line circuit, a station thereon having a loud-speaking telephone

set including a key and a dial, a second station normally disconnected from said intercommunicating line circuit and having a loud-speaking telephone set including a key, a central office, automatic switches thereat having terminals corresponding to said stations, means responsive to the actuation of the key at said first station for applying a busy potential to the central office switch terminal corresponding to said first station, means responsive to the actuation of the dial at said first station for testing the central office switch terminal corresponding to said second station, and means operating a predetermined interval of time after the central office switch terminal corresponding to said second station is tested and found idle for connecting a tone signal to the loud-speaking telephone set at said second station for reception by the loud-speaker thereat.

9. In a combined automatic telephone exchange and loud-speaking intercommunicating system, an intercommunicating line circuit, a station thereon having a regular telephone set including a dial, and a loud-speaking telephone set including a key and a dial, a central office, automatic switches thereat having switch terminals corresponding to said station, means responsive to the removal of the receiver of said regular telephone set and the actuation of the associated dial for disconnecting said station from said intercommunicating line circuit and extending a connection from said station to said central office by way of said switches, a second station normally disconnected from said intercommunicating line, other means responsive to the actuation of the key of said loud-speaking telephone set and the subsequent actuation of the associated dial for selectively signaling said second station, and means operating when the subscriber at said second station responds to the signal for connecting said second station to said intercommunicating line.

10. In a combined automatic telephone exchange loud-speaking intercommunicating system, an intercommunicating line circuit, a station thereon having a regular telephone set including a dial and a loud-speaking telephone set including a key and a dial, a central office, automatic switches thereat having switch terminals corresponding to said station, means responsive to the removal of the receiver of said regular telephone set and the actuation of the associated dial for disconnecting said station from said intercommunicating line circuit and connecting it to the terminals of said automatic switches for extending a connection thereover, a second station normally connected to corresponding terminals of said central office switches and disconnected from said intercommunicating line circuit, other means responsive to the actuation of the key of said loud-speaking telephone set and the subsequent actuation of the associated dial for selectively testing the switch terminals corresponding to said second station and signaling said second station and means operating when the subscriber at said second station responds to the signal for disconnecting said second station from its corresponding switch terminals and connecting it to said intercommunicating line circuit.

11. In a combined automatic telephone exchange and loud-speaking intercommunicating system, a subscriber's line circuit having a station thereon, a loud-speaking telephone set normally connected to the conductors of said line circuit, and a regular telephone set at said station, an

intercommunicating line normally associated with said line circuit, an automatic telephone exchange having automatic switch terminals corresponding to said line circuit, means responsive to the seizure of said terminals at said exchange for disconnecting said line circuit from said intercommunicating line and extending it to said switch terminals, means responsive to the transmission of signaling current over the established connection for disconnecting said loud-speaking telephone set from said line circuit and other means responsive to the removal of the receiver of said regular telephone set for opening the circuit to said signal current responsive means and for maintaining said loud-speaking telephone set disconnected from said line circuit.

12. In a combined automatic telephone exchange and loud-speaking intercommunication system, a primary station having a loud-speaking telephone set including a dial, an intercommunicating line, a plurality of secondary lines each having a station thereon and normally terminating in automatic switch terminals at a central office, a selector switch having a position individual to each of said secondary lines, means responsive to the actuation of said dial in accordance with a prearranged code for advancing said selector switch to the position corresponding to a called secondary line to which the prearranged code is assigned, means responsive to the arrival of said selector switch at said position for testing the called line, other means responsive to the arrival of said selector switch at said position and effective when the called line is found idle for signaling the called line, disconnecting it from its central office switch terminals and preparing it for connection to said intercommunicating line, and means effective when the called subscriber answers the signal for completing the connection of the called line to the intercommunicating line.

13. In a telephone conference system, a called station, a calling station, a line circuit normally connected to said calling station and disconnected from said called station, a dial at said called station, an automatic switch, a source of signaling current, means for connecting said signaling current to said line by way of said switch for a predetermined interval of time, means responsive to the actuation of said dial in accordance with a prearranged code for causing said automatic switch to operate said signal current connecting means and to prepare said called station for connection to said line, means effective at the expiration of the predetermined interval of time for releasing said automatic switch, and means controlled from said called station for completing the connection of said called station to said line independent of said automatic switch.

14. In a telephone conference system, a calling station, a plurality of called stations, a line circuit normally connected to said calling station and disconnected from said called stations, a dial at said calling station, a source of signaling current, an automatic switch responsive to the actuation of said dial in accordance with a prearranged code for connecting said signaling current to one of said called stations for a predetermined interval of time and for preparing said one of said called stations for connection to said line, means effective when said one of said called stations responds for completing the connection thereof to said line independent of said automatic switch, and means operating at the expiration of the predetermined interval of time during which

the called station is being signaled for releasing said automatic switch, whereupon said automatic switch becomes available for further control by said dial to selectively signal other of said secondary stations in accordance with other prearranged codes and to selectively prepare them for

connection to said line without disturbing the connection of said one of said called stations with said line.
